LUBRICATING EQUIPMENT CABINET

Arthur Fuller Dean, Glenview, and David C. Peterson, Chicago, Ill., assignors to Stewart-Warner Corporation, Chicago, Ill., a corporation of Virginia

Application March 10, 1949, Serial No. 1,324

Term of patent 14 years

(Cl. D52—2)

To all whom it may concern:

Be it known that we, Arthur Fuller Dean and David C. Peterson, citizens of the United States, residing at Glenview and Chicago, respectively, in the county of Cook and State of Illinois, have invented a new, original, and ornamental Design for a Lubricating Equipment Cabinet, of which the following is a specification, reference being had to the accompanying drawing, forming part thereof.

Fig. 1 is a perspective view; and

Fig. 2 is a plan view of a lubricating equipment cabinet showing our new design. The sides of the lubricating equipment cabinet not shown are the same in appearance as the sides shown.

We claim:

The ornamental design for a lubricating equipment cabinet, substantially as shown and described.

ARTHUR FULLER DEAN.
DAVID C. PETERSON.
